ERNST BOESE, FREDERICK BOESE, AND ABRAHAM NEUBERGER, OF CHICAGO, ILLINOIS.

Letters Patent No. 85,560, dated January 5, 1869.

IMPROVED BED-LOUNGE.

The Schedule referred to in these Letters Patent and making part of the same.

To whom it may concern:

Be it known that we, ERNST BOESE, FREDERICK BOESE, and ABRAHAM NEUBERGER, of Chicago, in the county of Cook, and State of Illinois, have invented a new and useful Improvement in Bed-Lounges; and we do declare that the following is a true and accurate description thereof, reference being had to the accompanying drawings, and to the letters of reference marked thereon, and being a part of this specification.

The nature of our invention consists in the arrangement of the additional head-piece, E, to the folding frame B, in such a manner that when the sofa is opened to be used as a bed, the head-piece E slides out, and is secured by hooks, F, catching into loops or eyes, H, and by the bolt K.

A, in the drawings, is the sofa-frame, to which the frame B is hinged, as shown.

C is the back, and

D, the head-piece, attached to and forming part of the frame A.

E is an additional head-piece, sliding over the piece D, and provided at its lower end with hooks, F, which catch in eyes or loops, H, on the head end of frame B, when the latter is turned over to form, with frame A, a bed, and the additional head-piece E is slid out.

When in this position, the head-piece E is further secured to the head-piece D by means of a bolt, K, as shown.

G are legs hinged to frame B.

The operation of our device is very simple, and does not need further description.

We do not claim all the parts described in this specification, nor their general combination, as we are well aware they are not new; but

What we claim as new, and desire to secure by Letters Patent, is—

The arrangement of the additional head-piece E with hooks F, in combination with eyes or loops, H, on hinged frame B, and bolt K, all operating as and for the purposes described.
